UNITED STATES PATENT OFFICE.

FRANCIS B. GRANGER, OF NEW YORK, N. Y., ASSIGNOR TO R. ROSS
APPLETON, OF SAME PLACE.

DESIGN FOR A BUSTLE AND HIP-FORM.

SPECIFICATION forming part of Design No. 32,077, dated January 2, 1900.

Application filed November 10, 1899. Serial No. 736,546. Term of patent 7 years.

To all whom it may concern:

Be it known that I, FRANCIS B. GRANGER, a citizen of the United States, and a resident of the city of New York, borough of Manhattan, in the county of New York and State of New York, have invented and produced a new and original Design for a Bustle and Hip-Form, of which the following is a full, clear, and exact description.

Reference is to be had to the accompanying drawings, forming a part of this specification, in which similar characters of reference indicate corresponding parts in both the figures.

Figure 1 is an inside plan view of a bustle and hip-form, showing my design; and Fig. 2 is a section on the line 2 2 of Fig. 1.

As shown in the drawings, the leading feature of my design for a bustle and hip-form consists of a body portion crescent-shaped when viewed in plan, within which is arranged a pad-like portion of a contour substantially that of the body portion, but having its edges spaced from the edges of said body portion.

Referring particularly to the drawings, 1 25 designates the body portion of substantially crescent form when viewed in plan, and arranged within the same is a pad or panel-like portion 2, having a substantially similar contour to the body portion, but transversely 30 curved to have a greater thickness at its longitudinal center than at its edges; and the minor features of the design consist in the lower part of the portion 2 being free from the body portion and the tab-like extensions 35 3 at the ends of the body portion.

Having thus described my invention, what I claim as new, and desire to secure by Letters Patent, is—

The design for a bustle and hip-form, as 40 herein shown and described.

In testimony whereof I have signed my name to this specification in the presence of two subscribing witnesses.

FRANCIS B. GRANGER.
